UNITED STATES PATENT OFFICE.

JAMES C. NORDGRAN, OF LOS ANGELES, CALIFORNIA.

DESIGN FOR A CASING FOR A DIRECTION SIGNAL AND STOPLIGHT.

Application filed October 12, 1925. Serial No. 15,097. Term of patent 14 years.

To all whom it may concern:

Be it known that I, JAMES C. NORDGRAN, a citizen of the United States, residing at Los Angeles, in the county of Los Angeles and State of California, have invented a new, original, and ornamental Design for Casing for a Direction Signal and Stoplight, of which the following is a specification, reference being had to the accompanying drawings, forming a part thereof.

In the accompanying drawings Fig. 1 is a front elevation of a casing for a direction signal and stop light showing my new design, and Fig. 2 is an end elevation thereof.

I claim:

The ornamental design for a casing for a direction signal and stoplight substantially as shown.

JAMES C. NORDGRAN.
